MACHINE FOR OPENING SHIPPING CASES FROM THE FLAT

Edgar Ardell, Jackson Heights, N. Y., assignor to
Standard-Knapp Corporation, Long Island
City, N. Y., a corporation of New York

Application March 14, 1940, Serial No. 323,878

29 Claims. (Cl. 93—6)

This invention relates to machines for opening folded or collapsed shipping or packing cases, folding the flaps of one or both ends in any desired manner to partially or wholly form the end walls and delivering the thus set-up cases for packing or otherwise. More particularly the invention relates to machines for opening such cases, partially forming, by flap folding, the end which is to become the bottom of the case and placing the thus-formed case upon the funnel or horn of a case packing machine.

In shipping or storing various articles such as cans or like containers containing food, beverages or other products, as well as rectangular cartons or packages containing cereals, confectionery and the like, or articles such as cakes of soap, etc., it is customary to place them in shipping or packing cases constructed of heavy fibrous material, for example, "corrugated board," fibre board or the like. These articles are packed in the shipping or packing cases by means of a case packing machine which usually is provided with a funnel, or horn, through which the charge of articles is pushed into the case. The shipping cases are placed in horizontal position partially telescoped upon the mouth of the funnel, being held there by a pivoted arm or "drop-off" lever until the charge is received. Then the drop-off lever lowers the filled case (turning it to upright position) onto a support such as a conveyor which carries the case to a sealing machine.

The shipping case blanks come from the manufacturer in collapsed condition, i. e., folded flat, for convenience in handling, and the operator of the case packer removes them one at a time from their shipping bundle and sets them up by hand, opening or squaring them up, folding the inner and outer flaps of one end closed, or nearly so, and spreading out the flaps at the opposite end which is to form the top of the case, and then places the case on the funnel of the case packer.

In food, beverage and other plants where the product is packed in cans, after filling and closing the cans, they commonly go to a labelling machine, thence to the case-packing machines and from there to the case-sealing machines. In many plants the delivery of cans at the beginning of such a line is substantially continuous, as, for example, in the case of can-filling machines, and the operation of all of the subsequent machines in the line is automatic so that the cans flow through the line constantly at a predetermined rate. The only part of the line that depends upon the human element is the setting up and placing of the shipping cases on the funnel of the case-packing machine. If the operator fails to supply the case packer with cases at a sufficiently rapid rate, either intentionally or otherwise, the operation of the entire packing line is interfered with.

Furthermore the outputs of the various machines has now been increased to such an extent that the manual setting up and placing of the shipping cases on the packer funnel is the limiting factor. For example, the packing machines are capable of delivering from 25 to 35 cases per minute, whereas from 15 to 20 cases per minute set up and placed on the case packer is about the maximum for manual operation, and this assumes that the operators work in 20 minute shifts.

The general object of the present invention is therefore to provide a machine for receiving the shipping cases "in the flat" and opening or squaring them up, appropriately folding their flaps, and delivering them to a desired station, or placing them on the funnel of the case-packing machine, at an extremely rapid rate, which is substantially higher than is possible by manual operation.

Another object is to provide a machine of this kind which will operate without attention other than keeping the magazine filled with folded or collapsed cases in the condition in which they are received from the manufacturer.

Another object of the invention is to provide such a machine which will positively open or square up the collapsed case and appropriately fold the flaps without damaging the case.

Another object of the invention is to provide a machine arranged in as small compass as possible so that it will not occupy an excessive amount of space.

The invention will be better understood and its advantages will be apparent from a consideration of the following description taken in connection with the accompanying drawings exemplifying a machine for setting up cases and placing them on the funnel of a can packer.

In these drawings:

Fig. 1 is a side elevation of the case opening machine with part of the magazine broken away;

Fig. 1a is a perspective view of a collapsed shipping case, and Fig. 1b a similar view of a shipping case which has been opened or squared up but whose flaps which are to form the bottom and top end walls have not been folded;

Fig. 2 is a view showing the machine partly in plan and partly in horizontal section taken on the broken line 2—2 of Fig. 1;

Fig. 3 is an enlarged sectional detail of the case feeding plunger taken on line 3—3 of Fig. 2;

Fig. 4 is an end view of the case opener and of a portion of the can packing machine onto the funnel of which the set-up packing cases are being delivered;

Figs. 5 and 6 are vertical sections, Fig. 6 being taken on line 6—6 of Fig. 4, illustrating the case opening or squaring-up mechanism. Fig. 5 shows this mechanism in engagement with a collapsed

case ready to open it, and Fig. 6 shows the position of the mechanism after the case is opened;

Fig. 7 is a horizontal section taken on line 1—1 of Fig. 1 illustrating the main shaft of the machine and associated parts;

Fig. 8 is a transverse section taken on line 8—8 of Fig. 1 showing the mechanism for spreading the outer flaps of the end of the case which is to form the bottom and also showing parts of the case delivery mechanism;

Fig. 9 is a horizontal section taken on broken line 9—9 of Fig. 8 showing the mechanism for folding the inner bottom flaps of the case;

Fig. 10 is a vertical section taken on line 10—10 of Fig. 8 showing the inner flap folding mechanism holding the inner bottom flaps closed and with one of the outer bottom flaps folded there-over, the opposite outer flap being left in its original position, the case being ready for delivery onto the funnel of the case packer;

Fig. 11 is a perspective view of a part of the mechanism illustrated in Fig. 10 for folding the upper outer flap;

Figs. 12 and 13 are enlarged views of the delivery mechanism for transferring the set-up case from the opening or squaring up station onto the funnel of the case packer;

Fig. 14 is a sectional view taken on line 14—14 of Fig. 7 showing the vacuum control valve of the squaring-up mechanism;

Figs. 15 and 16 are similar views taken respectively on lines 15—15 and 16—16 of Fig. 8 showing two cam operated timing switches forming part of the electrical control for the machine;

Fig. 17 is a diagrammatic view of the lower runway of the case packer provided with can operated control switches;

Fig. 18 is a diagram of the electrical connections of the control system;

Fig. 19 is a timing diagram showing the relative movements of the principal elements of the case opener; and

Figs. 20 and 21 (on sheet 1) are views showing the overlapping positions of a squared-up case leaving the squaring-up station and a collapsed case leaving the magazine and approaching the squaring-up station. Fig. 20 is a vertical section taken on line 20—20 of Fig. 21.

Referring to the accompanying drawings, Fig. 1a shows the shipping or packing cases made of corrugated board, or fibre board, or the like, as received from the manufacturer in flat, folded condition. These cases have major and minor side portions 1 and 2 to form the side walls or body of the case and corresponding extensions or flaps 3, 4 and 3' and 4'. The apparatus will also handle square cases. In Fig. 1b the collapsed case has been opened or squared up by bending the material of the sides at the creases or score lines 5 which are provided at the corners. The flaps 3, 4 and 3', 4', when folded, form the bottom and top end walls of the case (referring to the case in upright position after being packed with cans). The flaps 4 and 4' which are extensions of the minor side walls 2 are folded to closed position first and will be referred to as the inner flaps, while the flaps 3 and 3' are closed over them and will be referred to as the outer flaps.

In reference first to the general operation of the case opener, and tracing the progress of a case through the machine, the collapsed cases such as shown in Fig. 1a are fed one at a time from a storage magazine 6 by means of a reciprocating plunger 7 to a case opening or squaring up station indicated generally by reference nu-

meral S₁. The case being fed from magazine 6 is indicated by reference numeral A. A₁ (Fig. 5) indicates the case after reaching the opening station S₁ but while still in collapsed condition.

5 The case, after being squared up is indicated by A₂ and is in the condition shown in Fig. 1b with its flaps 3, 4, 3', 4' at both ends projecting straight out as extensions of the sides of the case. While at the opening station S₁ the two inner flaps 4 and 4' are folded to closed position and the outer flap 3 at the upper side of the case is folded downwardly at least partially over the inner flaps somewhat as shown in Figs. 10 and 13. The case is then advanced, in a direction 15 at right angles to the feeding movement, by means of a reciprocating carriage 8 to a delivery station S₂, which in the instance illustrated comprises the funnel 9_a of a can packing machine 9. A₃ indicates this position of the case.

20 The lower outer flap 3' is folded upwardly over the inner flaps by means of the drop-off lever 10 of the can packer as it rises to hold the case on the funnel. This completes the closing of all 25 end of the case which is to be the top are spread out by the funnel of the can packer as the case is pushed into slightly telescoping position there-on, but these flaps are not otherwise manipulated.

30 The case, after receiving a charge of cans from the can packer is turned to upright position A₄ by the drop-off lever 10 of the can packer and deposited upon a suitable conveyor, such, for example, as the roller conveyor 11 by means of 35 which it is carried to the next machine in the line, usually a sealing machine which seals both the closed but unsealed bottom flaps as well as the open top flaps.

The can packing machine 9 may be of any 40 suitable construction so long as it is provided with a drop-off lever (such as lever 10) which swings upwardly to hold the case in position on the funnel and downwardly after the case has received its charge of cans so as to turn the 45 case to upright position on the conveyor. The can packer which is indicated in Fig. 4 of the drawings is of the sort shown and described in Patent No. 2,127,924, granted August 23, 1938, to W. D. Kimball, Cornelius I. Braren and George P. Schaefer, except that it is arranged to pack three rows of four cans each instead of four rows of three cans each.

The cans are delivered in a single line through an inclined chute 12 into the mouth 13 of a dividing apparatus which distributes the cans equally into three runways (not shown), by means of which they are conveyed to three superposed shelves 14. The cans roll on their sides along the chute, through the divider, and along the runways and shelves 14. After the charging layer is formed on the shelves 14, the cans are pushed endwise by the pushers 15 through the funnel 9_a into the case. One of the can runways just referred to is illustrated in Fig. 17 and indicated by reference numeral 16 and will be referred to again later on.

The can packer is driven by its own independent source of power (not shown) such as an electric motor, which operates continuously. This motor, through a one-revolution clutch, indicated diagrammatically by numeral 17, drives an operating cam 18 which causes the plungers 15 to operate in such manner that a complete charge of cans is placed in the case each time the one-revolution clutch is tripped.

This clutch is tripped by the case opening apparatus in a manner hereafter to be described by means of a rod 19 pivoted at its right hand end to a hand lever 20 which is fixed to a cross shaft 21. Also fixed to shaft 21 is a short arm 22 which is connected by means of a chain 23 passing over idler sprocket 24 to the gripping member 25. Hence whenever rod 19 is shifted to the right as viewed in Fig. 4, it causes the tripping of the one-revolution clutch 17 and the 10 operation of the can packer to place a charge of cans in the case on the funnel.

This movement of rod 19 and rocking of lever 20 not only trips the one-revolution clutch 17, but also (and previous to tripping this clutch), 15 causes the drop-off arm 10 to rise from the dotted position to the full line position to hold the case on the funnel. This is effected by a pawl 26 fixed to shaft 21 which, when the shaft is rocked, is lifted to release it from a shoulder 27 behind which the pawl dropped when shaft 28, which carries drop-off arm 10, turned when the previous case was lowered to upright position on the conveyor 11. The details of this 20 drop-off mechanism are set forth in Patent No. 2,148,820, granted February 28, 1939, to Wallace D. Kimball, Cornelius I. Braren and John H. Mosley.

Referring now to the case opening apparatus, with the object of providing a machine which 30 will operate at a high rate of speed, the machine is arranged so that at approximately the same time that a case leaves the opening station S₁ to be delivered by the reciprocating carriage 8 to the delivery station S₂, a succeeding case leaves 35 the magazine 6. For this same reason and also in order to facilitate the manipulation of the flaps and to deliver the case in telescoping relation to the funnel 9_a, the delivery movement and the feeding movement are at right angles to one another.

Accordingly the feed plunger 7 is actuated by means of an oscillating lever 29 to which it is connected by a link 30, and the reciprocating carriage 8 is actuated by a second oscillating lever 31 to which it is connected by a link 32. Lever 29 is keyed to a horizontal shaft 33 and lever 31 to a vertical shaft 34, these shafts being 40 operatively connected by bevelled gearing 35. In this way the oscillating levers 29 and 31 are caused to move in unison and the desired oscillating movement is imparted to them by means of a crank 36 (Figs. 1 and 4) and a connecting link 37 which is pivoted to lever 29 at 38. Crank 36 is fixed to the end of the slow speed shaft 39 of a speed-reducing gearing which is contained within a housing 40. The high speed shaft 41 of this gearing is belted to a driving motor 42, this motor being provided with a solenoid 43, the operating coil of which is illustrated in Fig. 18.

The magazine 6 is a rectangular tower slightly larger in its dimensions than the folded cases and of a suitable height to hold a comparatively large quantity of these flat cases lying one upon another. The magazine is constructed of angle members 44 forming the corners and sheet metal sides 45 connecting these angle members. The side at the rear or left-hand side of the magazine as viewed in Fig. 1 is preferably omitted leaving the corner angle bars to guide the cases. This permits access to the cases should they fail 70 properly to feed downwardly. The side wall 45 at the front of the machine as viewed in Fig. 1 is terminated slightly above a dribbling device 75

46 and permits replenishing the magazine from this position.

The dribbling device 46 comprises a horizontal bar 47 having an inwardly rounded surface extending preferably throughout the width of the rear side of the magazine and one or more cam members 48 preferably attached to the bar. The purpose of this device is to limit the number of cases resting on the case A which is being fed, and hence limit the friction caused by the weight of these cases. The dribble device 46 is adjustable vertically so as to obtain the right pressure on the lowermost case A to cause the feeding plunger 7 to operate properly.

Dribble device 46 functions to cause the cases to be urged against the front wall of the magazine by the wedging action of cam members 48 and arrest the downward movement of the cases, each case being temporarily supported at its opposite edges by the bar 47 and the opposite wall of the magazine. This causes the case to bow downwardly at its center due to the weight of the cases above it. The bowed center of the case is supported by the cases below it. Inasmuch as these cases are continuously being removed by the feed plunger, however, the case resting on the dribble bar bows more and more until the end springs past the bar and joins the body of cases in the lower section of the magazine.

The magazine 6 is tilted away from the opening station S₁ as shown in Fig. 1, both to provide more space between the magazine and the setting-up mechanism at the opening station S₁, and in order to reduce the length of the delivery stroke of carriage 8, or in other words the distance through which the opened up case must be moved in order to place it on the funnel 9_a of the case packer. This is illustrated in Figs. 1 and 1a but will be described later on.

Feed plunger 7 slides on two parallel bars 49 positioned centrally below the magazine, and the case being fed out of the magazine is supported centrally by a pair of inclined rails 50 which are parallel with the bars 49. It is also supported at its side margins by a second pair of inclined rails 51. Rails 50 and 51 are inclined as far as the point indicated by reference numeral 52, beyond which these rails become horizontal so that the case in the position A₁ (Fig. 5) at the opening station is horizontal. Hence the case as it slides along the rails 50 and 51 under the action of plunger 7 undergoes a turning or dropping movement as the center of the case passes the point 52. This raises the rear of the case away from the inclined rails.

Plunger 7 has a cross member 53 upon the top of which is pivoted an adjustable main catch member 54 having a lip 55 biased upwardly by a helical spring 56 to engage the rear edge of the lowermost case to feed it forward. Due to the fibrous nature of the material of which the cases are made they possess considerable resiliency and this is apt to vary with changing climatic conditions. This varies the height of the center of the rounded edge of the case which is to be engaged by lip 55. For this reason and also to accommodate cases of inherently different thickness, it is desirable to make the height of lip 55 adjustable, as, for example, by means of adjusting screw 57. The height of lip 55 of the main catch is adjusted so that the upper edge of the catch member rubs lightly on the succeeding case B. This assures that the lip attains the best possible bite on the rounded edge

of case A which is being fed. The use of the adjustable dribble device 46 in the magazine also aids obtaining reliable action of the feeding plunger by maintaining uniform thickness of the successive cases being fed.

When the case emerges from the magazine—that is to say, as the rear edge of the case passes the front wall of the magazine, the pressure of the cases in the magazine is removed. The resilience of the fibrous material causes an expansion or thickening of the case which tends to raise the rounded rear edge of the case above the lip 55 of the main catch. Also the turning of the case after its center passes the point 52 of the supporting rails causes the rear edge of the case to move or swing upwardly out of range of the main catch. In order to overcome this difficulty an auxiliary catch 58 is provided. This catch is pivoted at 59 to the main catch and is biased upwardly by means of a second helical spring 60. A cross pin 61 limits its upward movement.

When plunger 7 is at the end of its rearward stroke, auxiliary catch 58 is held in depressed position with its lip slightly to the rear of lip 55 of the main catch by means of a member 62 which is preferably adjustably mounted on the rear of the magazine. As soon as the plunger moves forward enough for auxiliary catch 58 to clear the inner wall of the magazine, the catch moves upwardly under the action of spring 53 and slides along the lower surface of the next succeeding case B until case A emerges from the magazine when the auxiliary catch 58 is still held in depressed position by means of a member 63 which is mounted for vertical adjustment upon and projecting centrally from the front wall 45 of the magazine. However, member 63 is so adjusted that its lower surface (which may be either straight or curved as shown) permits auxiliary catch 58 to rise above the lip 55 of the main catch so that the plunger will continue to engage the case being fed and advance it against the stop 64 at the opening station S1.

Member 63 also serves an additional function. The sudden expansion or thickening of the rounded edge at the rear of the case A being fed, which takes place upon the release of the compression pressure of the cases above it as it emerges from the magazine, tends to make the case spring forward away from the plunger. It is important to prevent this because otherwise neither of the lips 55 or 58 may re-engage the edge of the case, in which event the case is apt to become jammed. Member 63 prevents this springing away since its position is the right distance from the point 52 on the rails to apply a degree of pressure to the rising upper surface of the case as the case turns vertically about point 52.

The main shaft 65 of the machine extends transversely beneath the opening station S1 and carries the series of cams which actuate the squaring-up mechanism, the flap folding mechanism and various control devices. This shaft is driven by means of a chain 66 from the slow speed shaft 39 of the reducing gear 46.

The squaring-up mechanism (Figs. 5 and 6) comprises one or more vacuum cups 67 arranged to engage the lower major side of the case and one or more vacuum cups 68 which engage the opposite major side of the case. These are timed by mechanism to be described so as to engage the case in the position shown in Fig. 5 at the 70

instant the front edge of the case reaches stop 64. Vacuum is simultaneously applied. As soon as this engagement takes place the plunger 7 releases the case and commences its return stroke.

5 Lower vacuum cups 67 are mounted on an arm 69 pivoted at 70 adjacent the stop 64 and the front end of the unfolded case. When no case is at the opening station, arm 69 rests upon a fixed stop 71 lowering the vacuum cup sufficiently to be out of the path of an incoming case. The arm is raised by means of a roller 72 on a rock member 73 which is pivoted on a bolt 74 (Fig. 7) passing through the rail members 50 which serve to support the central portion of the case at position A1. It is rocked in one direction by means of a cam 75 on main shaft 65, and in the opposite direction by a helical spring 76.

The upper vacuum cups 68 are mounted on an 20 arm 77 which by means of a parallelogram linkage indicated generally by numeral 78 is maintained always parallel to the horizontal portions of rails 50 and is swung from the position shown in Fig. 5 to the position shown in Fig. 6, to open 25 or square up the case. The two arms of the parallelogram linkage 78 are pivoted at 79 and 80 adjacent and in front of the stop member 64. One of these arms has a short extension 81 which by means of a link 82 is operatively connected 30 at 83 to the right hand end of rock member 73.

Arms 69 and 77 have air passageways shown in dotted lines in Fig. 6 by means of which the vacuum cups 67 are connected with a flexible tubing 84 and vacuum cups 68 to a tubing 85. These 35 tubes are preferably joined together and connected to a conduit 86 which leads to vacuum control valve 87 (Figs. 14 and 7). The inlet conduit 88 of this control valve is connected to a suitable source of vacuum (not shown). This valve 40 is opened and closed by a cam 89 on main shaft 65, the valve being opened during the period when the roller 90 is on the high part of the cam.

It will be understood that as the cam 75 rotates, vacuum cup arms 69 and 77 will be moved 45 into the position shown in Fig. 5 so as to cause vacuum cups 67 and 68 to engage the case in position A1, roller 91 on rock member 73 then being at the low spot of cam 75. As the cam rotates, rock member 73 is tilted about its pivot, 50 causing roller 72 to release the lower vacuum cup arm 79 and by a downward movement of link 82 causing the parallelogram linkage 78 to swing to the vertical position shown in Fig. 6, thereby lifting the upper major side of the case and 55 swinging the minor sides as indicated by the dotted arrows in Fig. 6 so as to square-up the case. The vacuum valve cam 89 is so timed as to open this valve about simultaneously with the engagement of the vacuum cups with the case in position A1 and to close it shortly after the right hand minor side of the case in position A2 engages stop members 92 and 93 which are appropriately positioned directly above stop 64.

As the case swings into squared-up position the 65 corner diagonally opposite stop 64 lifts a latch-like member 94 which is also the actuating lever of a case detector switch 95, closing this switch for a short interval, the switch being opened again as soon as the lever 94 drops behind the left hand side wall of the case as shown in Fig. 6 to hold the case in squared-up position against the stops 92 and 93. This detector switch is included in the circuit diagram of Fig. 18 which will be referred to later on.

The cases as they come from the manufacturer

are scored at the base of each flap so as to facilitate the bending of the flap, but even so the hinge is quite stiff and resistant to bending, and not infrequently the flap has a tendency to bend at one side or the other of the score line which would make the flap either too short or too long and interfere with the proper closing of the end of the case. It is possible to provide straight edges along the exterior bottom and top sides of the case at the score lines to assure the formation of the hinge of the flap in a straight line, but this is not so easy to accomplish as to the inner flaps which extend from the vertical sides of the case. If these sides bulge even to a small extent at the time the inner flaps are folded, the case is liable to buckle in such a manner as to seriously weaken it and even to destroy its usability. I have devised a method for manipulating both the outer and inner flaps which avoids this difficulty and assures that the flap hinges are straight and correctly positioned at the base of each flap.

In accordance with this method, I first spread outwardly the two outer flaps as shown, for example, in Fig. 8, preferably engaging the outer surfaces of the upper and lower sides of the case with straight edge members 96 and 97 which are disposed exactly at the base of each flap where it is desired to have the bending take place to form the flap hinge. The spreading of these outer flaps 3 and 3' places the vertical side walls of the case under tension and stretches them straight, the tension being the greatest just before the flap hinges "break." While the vertical side walls of the case are placed under tension in this manner, I commence the folding of the inner flaps 4 and 4' which extend from these vertical walls. Inasmuch as the "breaking" of the hinges of these inner flaps takes place while the vertical walls are under such tension, and therefore without bulges, the hinges form straight and at the correct locations. The outward spreading of the outer flaps 3 and 3' having "broken" the flaps at the score lines, the flaps may then easily be folded inwardly to closed position later on.

The particular flap-spreading and flap-folding mechanism which I have provided is illustrated in several of the figures, particularly Figs. 8, 9, 10 and 7. These mechanisms are driven from a short shaft 98 which in turn is driven by a bevelled gearing 99 from main shaft 65. The flap-spreading members are shown at 100 in Fig. 8 and are arranged to rotate continuously in opposite directions on two parallel horizontal shafts 101 and 102. They engage the flaps near their outer edges and as soon as they have spread them slightly more than indicated in Fig. 8, the spreading members rotate past the edges of the flaps and release them.

Shaft 101 of the upper flap spreader 100 is driven by means of a chain 103 which passes over a pair of idler sprockets 104 and around a driving sprocket 105. This sprocket is fixed on a short collar 106 which also has a second sprocket 107 fixed thereon. Passing around sprocket 107 is a main driving chain 108 which passes over an idler sprocket 109 and thence around driving sprocket 110 on shaft 98. The back of this chain then drives a sprocket on a second collar 111 which drives this collar in the opposite direction of rotation from that of shaft 101. A second sprocket 112 fixed to this second collar drives shaft 102 by means of a short chain 113, so that shaft 102 and shaft 101 are driven in opposite directions.

The straight edge members 96 and 97 are located one directly above the other, and the case as it is fed to the position S₁ by the feeding plunger 7 is correctly positioned to bring the edges of these members 96 and 97 at the respective score lines of the flaps 3 and 3' by means of adjustable guides 114 (Fig. 2). The upper straight edge member 96 is mounted on the frame of the machine by means of two parallel extensions 115. Stop 92 is preferably integral with member 96 as shown in Fig. 1. Lower straight edge member 97 is formed with an angle bar secured to one of the rail members 50.

The folders for the inner flaps are mounted upon two vertical parallel shafts 116 and 117 which also rotate continuously in opposite directions and are driven by bevelled gearing 118 and 119 from shaft 98. On each of the vertical shafts 116 and 117 there are two auxiliary folders 120 and one main folder 121. Each of the auxiliary folders 120 is an L-shaped member (to reach around the end of the flap) having a roller 122 at its outer end. The main folder 121 has a long straight arm from the end of which a curved wiping portion 123 extends to a point opposite the end of auxiliary folder 120, its outer surface being slightly to the rear of the surface of roller 122, so that as the folders rotate, the roller will strike the surface of the flap first.

In operation the two auxiliary folders carrying the rollers 122 engage one of the inner flaps at two spaced points as shown in Fig. 10 and at a position towards the outer edge of the flap away from its base as shown in Fig. 9. These auxiliary folders are thus able to exert sufficient pressure against the flaps without marring them so as to initially "break" the base of the flap at the score line and thus form the hinge 124. It will be remembered that the vertical side walls 30 of the case from which these inner flaps 4 and 4' extend are being held straight under the tension imparted by the spreading members 100 at the instant that this "breaking" of the hinges 124 of the inner flaps 4 and 4' by rollers 122 takes place. The curvature of the folding portions 123 of the main flap folders 121 is such that very shortly after the initial movement of the flaps by rollers 122, these curved portions contact the surfaces of the flaps and move them with a wiping action to fully closed position as shown in full lines in Fig. 9.

During the squaring up of the case and the folding of the inner flaps the carriage 8 returns from its delivery of a previous case to the full line position shown in Figs. 12 and 13. The squaring up of the case is completed, however, during the first half of this return stroke so that the suspending or supporting members 125 and 126 (Fig. 10) which are provided on carriage 8 for conveying the case to the delivery station may pass one on either side of the case at position A₂ without striking it. Suspending member 125 extends vertically the full height of the case and is provided at the bottom with a lip 127 for supporting the case. Member 126 fits around the diagonally opposite corners of the case engaging both the top and side margins.

Delivery carriage 8 is provided with a pivoted pushing arm 128 which pushes the squared-up case A₂ forward while it is held by the members 125 and 126 which hold the case in squared-up condition after it leaves the squaring up station S₁ where it is thus held by the stops 64, 92 and 93 and the catch lever 94. Pushing arm 128 is arranged to be lifted to the horizontal position

shown in Fig. 12 during the return stroke of the carriage 8 so as to clear the top of the case A₂. Pushing arm 128 then swings downwardly to the vertical position shown in Fig. 13 so as to push the case forward and also for the purpose of folding the upper outer flap 3.

In order to carry out these operations, pushing arm 128 is fixed to the left hand end of a shaft 129 (Fig. 10), this shaft having a helical spring 130 which urges the pushing arm towards the horizontal position. Pushing arm 128 has a short extension 131 which carries a roller 132 for engaging a holding bar 133, the function and operation of which will shortly appear.

In order to swing arm 128 to the lower or vertical position, the opposite end of shaft 129 is provided with a control arm 134 having a roller 135 which is engaged by a vertically movable short control bar 136. This control bar is carried by a head piece 137 at the upper end of a vertical rod 138 which extends downwardly alongside of main shaft 65. This rod slides in suitable brackets carried by the machine frame and fixed upon it near its lower end there is a member 139 carrying a roller 140 which cooperates with a cam 141 on main shaft 65.

As cam 141 permits member 139 and rod 138 to move downwardly under their own weight, control bar 136 depresses roller 135 and control arm 134 thereby swinging pushing arm 128 from the horizontal to the vertical position as shown in Fig. 13. This movement is timed to take place just after the inner flaps are folded and during the initial forward or delivery stroke of carriage 8, as may be seen from the timing diagram, Fig. 19. This at least partially folds the upper outer flap 3 over the closed inner flaps and starts the case on its delivery movement.

This movement swings extension 131 from its 45° position to the right, as shown in Fig. 12, to a 45° position to the left, as shown in Figs. 11 and 13. Inasmuch as control bar 136 overlaps holding bar 133, roller 132 on extension 131 will engage the lower surface of the holding bar before roller 135 of control arm 134 is released by control bar 136, and as shown in Fig. 11, holding bar 133 will consequently maintain pushing arm 128 in its vertical position until carriage 8 reaches the end of its delivery stroke. When roller 132 leaves the right hand end of holding bar 133 it engages the vertical face of a stop 142. The final movement of the carriage causes pushing arm 128 to force the case in position A₃ onto the funnel 9_a of the canpacking machine and firmly fold the outer flap 3 against the bottom of the case where it is held by the drop-off lever 10 which rises to vertical position at this time.

During the first part of the return stroke of carriage 8, roller 132 rolls first upwardly and then downwardly on the vertical face of stop 142 as helical spring 130 on shaft 129 returns pushing arm 128 to horizontal position as shown in dotted lines in Fig. 12. Extension 131 has now swung back to its original right hand position and roller 132 again engages the lower surface of holding bar 133. Before the return stroke of the carriage is completed, cam 141 will have raised rod 138 and control bar 136 to their original upper position, as shown in Fig. 12 and in dotted lines in Fig. 11 so as to be ready for a repetition of the cycle just described in order to deliver the next succeeding case.

The operation of the case-opening apparatus has been described along with the description of the construction so that a repetition is believed

unnecessary, particularly in view of the timing diagram (Fig. 19) which shows diagrammatically the sequence of operations.

In view of the fact that the timing is so arranged that a new case is fed out of the magazine 6 at about the same instant that the squared-up case leaves the squaring-up station S₁, and since these two movements are at right angles to one another, a considerably longer delivery stroke would be required, thus making the apparatus occupy more floor space, were it not for the arrangement of the slideway for the collapsed cases leaving the magazine which is disposed at an angle to the case support at the opening station S₁. This is evident from Figs. 20 and 21. The upper surfaces of the left hand portion of rails 50 being inclined as far as the point 52, and the portion of these rails to the right of this point being horizontal, the forward edge of case A can overlap the lower outer flap 3' of case A₂ which is moving out of the squaring-up station S₁ and towards the case position A₃ on the funnel of the can packer. But for this overlapping, either the feeding stroke or the delivery stroke would have to be increased by approximately the width of flap 3'.

In order to control the operation of the case opener and the can packer, the operation of the can packer is made dependent upon that of the case opener. That is to say, the case opener initiates the operation of the can packer each time a case is placed on the can packer funnel 9. In addition, automatic controls are provided for stopping the case opener, should the supply of cans in the can packer reach a predetermined low point, and for re-starting the case opener as soon as the supply of cans is replenished. Also provision is made for stopping the case opener should the supply of cases run out in magazine 6 and no case be delivered onto the can packer funnel, or should the squaring-up mechanism fail to open up the case at the case opening station.

The control for stopping the case opener if the supply of cases runs out is mechanical. The initiation of the operation of the can packer is effected by a shifting of rod 19 (Fig. 4) to the right as described previously. This shifting is produced by means of a face cam 143 on main shaft 65. This cam cooperates with a roller 144 arranged near one end of a centrally pivoted lever 145 (Fig. 7) having a spring 146 which biases the roller against the cam. This lever is connected at its opposite end to rod 19, and when roller 144 rides into the valley of the cam, under the pressure of spring 146, rod 19 is shifted to the right and actuates the tripping lever 20 of the can packer.

However, a catch mechanism is provided at one end of lever 145 to prevent this movement in the event that no case has been delivered onto the funnel 9_a of the case packer. This catch mechanism comprises a plate 147 on lever 145, and a co-operating catch lever 148 which is pivoted to move into and out of the path of plate 147. This lever is actuated by a rod 149, connected to a lever 150 adapted to be engaged by the lower flap of the case when properly placed in position A₃ on the can packer funnel.

The control of the case opener which is responsive to the supply of cans in the case packer and to the failure of the squaring-up mechanism properly to square up a case is electrical and is included in the diagram of connections illustrated in Fig. 18. The driving motor 42 of the

case opener illustrated is a three-phase A. C. motor having three leads 151. The coil 43 of the solenoid brake is connected between two of these leads so that this coil is energized to release the brake whenever the motor is energized.

The motor leads 151 are connected through the main contacts 152 of a main switch 153 to the supply conductors 154, 154a and 154b. Main switch 153 is an electromagnetically operated switch having an operating coil 155 which, when energized, closes the main switch contacts as well as a pair of holding contacts 156.

Manual control of the case opener operation is provided for by means of a push button control switch 157. Included in this switch there is a normally open starting switch 158, a normally closed stopping switch 159 and a three-position control switch 160. With control switch 160 in the "hand" position, the motor 42 can be started by pushing the start switch 158 but the motor will operate only so long as this switch is held closed by hand. The circuit established by closing this switch comprises a conductor 161 from supply line 154a to operating coil 155 of the main switch, thence through conductor 162 to contact 163 of control switch 160, through this switch to conductor 164 and thence through the contacts of starting switch 158 to conductor 165 which is joined to a conductor 166 leading back to supply conductor 154.

When control switch 160 is in the "neutral" position, it is impossible to energize main switch 153 in any way and hence impossible to operate motor 42.

When control switch 160 is moved to the "automatic" position shown in full lines in Fig. 18, the energization of operating coil 155 of main switch 153 is placed under the control of a relay 167. This, as will be seen presently, (1) enables motor 42 to be stopped by pushing the stopping switch 159; (2) causes the automatic stopping of motor 42 in the event no case has been squared up at the squaring-up station S1; (3) stops motor 42 in case the supply of cans in the can packing machine is low; (4) automatically restarts motor 42 as soon as the supply of cans returns to normal.

Assuming that control switch 160 is in the "automatic" position, pressing the starting switch 158 will close a circuit from supply conductor 154, conductors 166 and 165, then through the starting switch to conductor 164 and control switch 160 to a conductor 168 which leads to the operating coil 169 of relay 167; thence through conductor 170 to conductor 161 and supply conductor 154a. This causes the relay armature to rise, closing its main contacts 171 and closing holding contacts 172. Closing main contacts 171 energizes coil 155 of the main switch through circuits to be described.

The closing of holding contacts 172 establishes a circuit which keeps relay 167 in its closed position after the starting switch 158 is released. This circuit is from conductor 165 through the normally closed contacts of stopping switch 159 to conductor 173; thence through the contacts of a normally closed timing switch 174 having a roller 175 which cooperates with a cam 176 on main shaft 65 to open and close this switch. The circuit continues from switch 174 through conductors 177 and 178 through controlling contacts 172, conductor 179, conductor 180, relay operating coil 169 and conductors 170 and 161 to supply conductor 154a.

Obviously, pressing the stopping switch 159 opens this circuit, de-energizes the relay coil 169

and therefore opens the main switch 153 stopping motor 42.

The opening of timing switch 172 will have the same effect and cam 176 is timed so that roller 175 will open switch 174 during the latter part of the operation of the vacuum cup mechanism to open the case, as is to be seen from Fig. 19. As previously described, however, the case-detector switch 95 is closed momentarily as its actuating lever is raised by the corner of the case during the final squaring up movement. The timing is such that under normal operation switch 95 will be closed while timing switch 174 is opened, and as the contacts of switch 95 are in parallel with the contacts of switch 174, the holding circuit of operating coil 169 of the relay will not be opened. Should the squaring-up mechanism fail properly to square up a case so as to close switch 95, however, this circuit would be opened by the opening of switch 174 and this would de-energize the relay coil and stop motor 42.

The automatic stopping of motor 42, should the supply of cans in the can packer become low, and the re-starting when the supply is replenished, is accomplished by means of a low supply stopping switch 181 and a high supply starting switch 182, and by means of a normally closed cam operated timing switch 183. The low and high switches 181 and 182 are actuated by pivoted counterbalanced can runway sections 184 and 185, respectively, as illustrated in Fig. 17.

Under normal conditions of operation, low stopping switch 181 is closed and high starting switch 182 is open, just the same as the main stop and start buttons 159 and 158. Should the supply of cans shown in solid lines on the runway be reduced somewhat, the pivoted runway section 184 would rise, opening stopping switch 181, and this, as will presently be seen, de-energizes the operating coil 155 of main switch 153, thereby stopping motor 42. Thereafter as soon as the supply of cans increases to about the extent shown by the dotted lines in Fig. 17, low switch 181 will be re-closed and high starting switch 182 will also be closed. This re-energizes coil 155 and re-starts the case opener motor 42.

The circuit arrangement is such, however, that when the low supply stopping switch 181 is opened, motor 42 will be maintained in operation until the feed plunger 7 and the delivery carriage 8 have completed their strokes and returned to their initial positions. This effect is produced by means of the timing switch 183 which is actuated by means of a roller 186 which cooperates with a cam 187 on main shaft 65 so positioned as to open the switch only when the plunger and carriage are at the end of their inward or return strokes.

The function of relay 167 is to place the control of the operating coil 155 of the main switch, in these three switches 181, 182 and 183. The energizing circuit of coil 155 has previously been traced from supply conductor 154a through the coil and to conductor 162. From this conductor the circuit is through conductor 188, through main contacts 171 of the relay 167 and then to a conductor 189. The circuit from this point back to the supply conductor 154 may be completed in either of two ways. So long as the supply of cans is normal (that is, the number of cans on the runway is not depleted enough to open low switch 181), the circuit is through conductor 190 holding contacts 156 of main switch 153, conductor 191, conductor 193, low supply stopping switch 181 and conductors 193, 194 and

166 to supply conductor 154. Should the supply of cans reach a point low enough to open switch 181, the circuit would then be temporarily maintained from conductor 191 through conductor 195, timing switch 183 and conductors 196 and 166 back to supply wire 154, so that main switch 153 would not open until the plunger 7 and carriage 8 returned to their initial positions, at which instant timing switch 183 would open and stop the motor 42.

Assuming the machine has been thus stopped due to the supply of cans being depleted, when the supply is replenished so that the high supply starting switch 182 is closed, a circuit will be established from the main contacts 171 of relay 167 (which is still held in its upward or closed position), through conductor 189, conductor 196, switch 182 and conductors 197, 194, and 166 back to supply conductor 154. This re-establishes the circuit through operating coil 155 of main switch 153 and closes this switch, thereby re-starting the operating motor 42 of the case opener.

Because of the arrangement and timing of the present case opening apparatus, it is intended to square up corrugated board or fibre board shipping cases and place them on the funnel of a case packing machine at a rate of operation higher than is attainable by hand opening even when several men are operating in short shifts, and also at a considerably higher speed than is attainable with any apparatus of which I am aware.

It will be understood that the above description and the appended drawings exemplify my improved apparatus for opening shipping cases and delivering them to a delivery station, together with the automatic controls which I have devised for operating this machine in association with a case packing machine, but that the purpose of such disclosure is merely for illustrative purposes rather than to delimit the invention. It will therefore be understood that changes may be made in the construction of the apparatus, the method of procedure and the arrangements for automatic control without departing from the spirit or scope of my invention which is set forth in the appended claims.

I claim:

1. In a machine for opening shipping cases from the flat, a magazine for holding collapsed cases, reciprocating feeding means for feeding the cases one at a time to an opening station, means for squaring up the case at the opening station, and reciprocating delivering means operating at substantially right angles to the feeding means for advancing the squared-up case to a delivery station, and means for reciprocating the feeding means and the delivering means simultaneously so as to cause a collapsed case to leave the magazine at approximately the same instant that a squared-up case leaves the opening station.

2. In a magazine for opening shipping cases from the flat, a magazine for holding collapsed cases, feeding means for feeding cases one at a time to an opening station, means for squaring up the case at the opening station, reciprocating delivery means operating at substantially right angles to the feeding means for advancing the squared-up case to a delivery station, said delivery means including a carriage, and means for slidably supporting the same, said carriage having members to cooperate with the squared-up case to hold it in squared-up position.

3. In a machine for opening shipping cases from the flat, a magazine for holding collapsed

cases, feeding means for feeding cases edgewise one at a time to an opening station, means for squaring up the case at the opening station, reciprocating delivery means operating at substantially right angles to the feeding means for advancing the squared-up case to a delivery station, said delivery means including a carriage having means for engaging the upper side margins of the case and a pushing member for engaging the rear of the case.

4. In a machine for opening shipping cases from the flat, a magazine for holding collapsed cases, feeding means for feeding cases edgewise one at a time to an opening station, means for squaring up the case at the opening station, reciprocating delivery means operating at substantially right angles to the feeding means for advancing the squared-up case to a delivery station, said delivery means including a carriage having means for engaging the upper side margins of the case and a pushing member for engaging the rear of the case, and means for controlling said arm to cause it to fold the adjacent flap at the rear of the case prior to pushing the case forward and to clear the next succeeding case on the return movement of the delivery means.

5. In a machine for opening shipping cases from the flat, a magazine for holding collapsed cases, means for feeding the same one at a time from the magazine to an opening station having case-supporting means, mechanism for squaring up the case at the opening station, means operating simultaneously with said feeding means for advancing a squared-up case to a delivery station, said movement being at about right angles to the feeding movement of the case, and said feeding means including a slideway for the collapsed cases which is disposed at an angle to the case-supporting means at the squaring up station.

6. In a machine for opening shipping cases from the flat, a magazine for holding collapsed cases, means for feeding the same one at a time at right angles to the axis of the magazine to an opening station, case-supporting means at said station, mechanism for squaring up the case at the opening station, means operating simultaneously with said feeding means for advancing a squared-up case to a delivery station, said movement being at about right angles to the feeding movement of the case, the axis of said magazine being tilted with respect to the axis of the case when squared up at the opening station, whereby the collapsed cases are delivered to the opening station at an angle to the case-supporting means thereof.

7. In a machine for opening shipping cases from the flat, a magazine for holding a stack of collapsed cases, a reciprocating plunger arranged to slide the cases one at a time from the bottom of the magazine, an upwardly biased main catch carried by the plunger for engaging the rear edge of the lowermost case of the stack to push it forward, said catch having limited upward movement to avoid scarring the adjacent case in the stack, the engageable portion of the rear edge of the case rising out of range of said catch after the case leaves the stack, and an auxiliary catch carried by the plunger arranged to move upwardly and engage the case as the rear edge thereof rises out of range of the main catch.

8. In a machine for opening shipping cases from the flat, a magazine for holding a stack of collapsed cases, a reciprocating plunger arranged to slide the cases one at a time from the bottom of the magazine, an upwardly biased catch car-

ried by the plunger for engaging the rear edge of the lowermost case of the stack to push it forward, said catch having limited upward movement to avoid scarring the adjacent case in the stack, and means for adjusting the limit of the upward movement of the catch in order to accommodate cases of different thickness.

9. In a machine for opening shipping cases from the flat, a magazine for holding a stack of collapsed cases, a reciprocating plunger arranged to slide the cases one at a time from the bottom of the magazine, the cases being resilient and tending to expand in thickness when the pressure of the stack is removed, an upwardly biased catch carried by the plunger for engaging the rear edge of the lowermost case of the stack to push it forward, said catch having limited upward movement to avoid scarring the adjacent case of the stack, and a dribble bar within the magazine to limit the weight of the stack resting on the bottom case so as to keep the successive bottom cases compressed to uniform thickness to suit the height of said catch.

10. In a machine of the class described, a magazine for holding a stack of collapsed cases, a reciprocating plunger arranged to slide the cases one at a time from the bottom of the magazine, a slideway for supporting the cases, the outer portion of said slideway changing its direction so as to cause the front of the case to drop and the rear of the case to rise, and a guide member to frictionally engage the upper surface of the rear margin of the case as the rear of the case rises so as to prevent the resiliency of the case from causing it to spring away from the plunger.

11. In a machine for opening shipping cases from the flat, a magazine for holding collapsed cases, means for feeding them one at a time from the magazine to an opening station, a stop at said station for engaging the forward edge of the collapsed case, means for squaring up the case while maintaining it in engagement with said stop, a control circuit including a switch the opening of which stops the machine, and an actuating lever therefor arranged to be moved by the corner of the case diagonally opposite from said stop, said lever being adapted to engage the squared-up case to engage said corner of the case after it is squared up to maintain the case in squared-up condition.

12. In a machine for opening shipping cases from the flat, a magazine for holding collapsed cases, means for feeding them one at a time from the magazine to an opening station, a stop at said station for engaging the forward edge of the collapsed case and mechanism for squaring up the case at the opening station comprising a vacuum cup for holding one side of the case and a parallelogram linkage mechanism pivoted adjacent said stop and carrying an arm all positions of which are parallel to one another, a vacuum cup on said arm for engaging the opposite side of the case and means to actuate said linkage mechanism.

13. In a machine for opening shipping cases from the flat, a magazine for holding collapsed cases, means for feeding them one at a time from the magazine to an opening station, a stop at said station for engaging the forward edge of the collapsed case and mechanism for squaring up the case at the opening station comprising an upwardly shiftable vacuum cup adjacent the lower side of the case and a parallelogram linkage mechanism pivoted adjacent said stop and carrying an arm all positions of which are parallel

to one another, a vacuum cup on said arm for engaging the upper side of the case, and actuating means for shifting the first vacuum cup upwardly into engagement with the lower side of the case and for swinging the linkage mechanism to bring the second vacuum cup into engagement with the upper side of the case and thereafter swinging said mechanism in the opposite direction to open the case.

14. In a machine for opening shipping case blanks from the flat, means for supporting a case blank in squared-up position including rigid members having a substantially straight edge supporting the exterior of the case body adjacent the flap fold lines of two opposite sides, and means for spreading the flaps forcing their fold lines against the straight edges of said supporting members to initially bend them along these fold lines to facilitate the subsequent closing of the flaps.

15. In a machine for opening shipping case blanks from the flat, means for supporting a case blank in squared-up position including members engaging the exterior of the case body adjacent the flap fold lines of two opposite sides, rotary devices for spreading the flaps to initially bend them along these fold lines to facilitate the subsequent closing of the flaps, and rotary devices operating during the spreading of said flaps for folding the intermediate flaps.

16. In a machine for opening shipping case blanks from the flat, means for supporting a case blank in squared-up position, and means for folding a flap thereof to closed position comprising main and auxiliary rotary folders, the auxiliary folder engaging the flap to break the same along its fold line, and the main folder engaging the broken flap to fold it to closed position, and means for rotating said folders.

17. In a machine for opening shipping case blanks from the flat, means for supporting a case blank in squared-up position, means for folding a flap thereof during formation of an end wall of the case comprising main and auxiliary folders, the auxiliary folder engaging the flap to break the same along its fold line, and the main folder engaging the broken flap to fold it to closed position, a common shaft carrying said folders, and means for rotating the same.

18. In a machine for opening shipping case blanks from the flat, means for supporting a case blank in squared-up position, means for folding a flap thereof to closed position comprising a shaft disposed outwardly from the flap hinge and arranged to rotate in parallel relation thereto, and means for rotating the shaft, said shaft carrying an auxiliary folder arranged to engage the outer portion of the flap to initially bend the same at its hinge portion, and a main folder on said shaft arranged to contact the flap progressively closer to the flap hinge as the shaft rotates thus folding the flap to closed position.

19. In a machine of the class described, a case packing machine having a funnel for receiving thereon a case to be filled and including a storage runway for articles to be packed, a case opening machine adapted to receive collapsed cases, square them up and deliver them to the funnel of the case packing machine, mechanism actuated by the articles in the storage runway for stopping the operation of the case opening machine when there is a failure in the supply of articles in the storage runway, and means actuated by the articles in the storage runway for re-starting the case-opening machine when the

supply of articles in the storage runway is restored.

20. In a machine for opening shipping cases from the flat, a magazine for holding collapsed cases, means for feeding said cases one at a time from the magazine to stationary position at a squaring-up station and mechanism for squaring up the case at said station comprising a lower pair of suction cups to engage the bottom side of said collapsed case, an upper pair of suction cups adapted to engage the top side of said case and parallel-motion mechanism for raising the upper pair of suction cups while maintaining them parallel with the lower suction cups so as to square up the case.

21. In a machine for opening shipping cases from the flat, a magazine for holding collapsed cases, means for feeding said cases one at a time from the magazine to stationary position at a squaring up station and mechanism for squaring up the case at said station comprising a lower pair of suction cups to engage the bottom side of said collapsed case, an upper pair of suction cups to engage the top side of said case and parallel-motion mechanism including an arm pivoted adjacent the lower side of the case and carrying the upper pair of suction cups and adapted to swing them upwardly while maintaining them parallel with the lower side of the case thereby to square up the case.

22. In a machine for opening shipping cases from the flat, a magazine for holding collapsed cases, means for feeding said cases one at a time from the magazine to stationary position at a squaring up station and mechanism for squaring up the case at said station comprising a lower pair of suction cups to engage the bottom side of said collapsed case, an upper pair of suction cups to engage the top side of said case and parallel-motion mechanism including an arm pivoted in the plane of the lower side of the case and carrying the upper pair of suction cups and adapted to swing them upwardly while maintaining them parallel with the lower side of the case thereby to square up the case.

23. In a machine of the class described, the combination of case packing mechanism having a predetermined cycle of operation for inserting a charge of articles within a case and having a funnel through which the charge is passed into the case, a tripping device for initiating the said cycle of operation, squaring up mechanism having a predetermined cycle of operation independent of said packing mechanism including means for squaring out case blanks and delivering them successively to said funnel, tripping device actuating means operated in timed relation to the squaring-up mechanism to actuate said tripping device in timed relation to the delivery of each successive case to said funnel, and means actuated by the case on the funnel for controlling said tripping device actuating means.

24. In a machine of the class described, the combination of case packing mechanism having a predetermined cycle of operation for inserting a charge of articles within a case and having a funnel through which the charge is passed into the case, a tripping device for initiating the said cycle of operation, squaring up mechanism having a predetermined cycle of operation independent of said packing mechanism including means for squaring out case blanks and delivering them

successively to said funnel, tripping device actuating means operated in timed relation to the squaring-up mechanism to actuate said tripping device in timed relation to the delivery of each successive case to said funnel, means for restraining the operation of said actuating means, and means actuated by the case on the funnel for shifting the restraining means to cause it to permit actuation of the tripping device.

10 25. In a machine for opening shipping cases from the flat, a magazine for holding collapsed cases, means for feeding them one at a time from the magazine to an opening station, mechanism operating while the case is at rest at the opening station for squaring-up the case, devices operating while the case is in stationary position at the opening station for folding the flaps thereof to form one end of the case, and delivering means for moving the squared-up case from the opening station.

15 26. In a machine for opening shipping cases from the flat, a magazine for holding collapsed cases, means for feeding them one at a time from the magazine to an opening station, mechanism operating while the case is at rest at the opening station for squaring-up the case, rotary devices at the opening station adjacent one end of the squared-up case adapted to fold the flaps at that end of the case to form one end to the case, and delivery means for removing the squared-up case from the opening station.

20 27. In a machine for opening shipping cases from the flat, a magazine for holding collapsed cases, means for feeding them one at a time from the magazine to an opening station, mechanism operating while the case is at rest at the opening station for squaring-up the case, devices operating while the case is in stationary position at the opening station for folding the flaps thereof to form one end of the case, delivering means for removing the squared-up case from the opening station, and means for actuating said feeding means and delivering means simultaneously.

35 28. In a machine for opening shipping cases from the flat, a magazine for holding collapsed cases, means for feeding them one at a time from the magazine to an opening station, mechanism operating while the case is at rest at the opening station for squaring-up the case, devices operating while the case is in stationary position at the opening station for folding the flaps thereof to form one end of the case, delivery means for removing the squared-up case from the opening station, and means for actuating said feeding means and delivering means simultaneously.

40 29. In a machine for opening shipping cases from the flat, a magazine for holding collapsed cases, means for feeding said cases one at a time from the magazine to stationary position at a squaring-up station and mechanism for squaring up the case at said station comprising a lower pair of suction cups to engage the bottom side of the collapsed case, an upper pair of suction cups to engage the top side of said case and parallel-motion mechanism carrying the upper pair of suction cups and adapted to swing them upwardly while maintaining them parallel with the lower side of the case thereby to square-up the case.
